UNITED STATES PATENT OFFICE.

JOHN N. VALLEY, OF JERSEY CITY, NEW JERSEY.

ELEVATED RAILROAD.

SPECIFICATION forming part of Letters Patent No. 408,941, dated August 13, 1889.

Application filed January 25, 1889. Serial No. 297,519. (No model.)

To all whom it may concern:

Be it known that I, JOHN N. VALLEY, of Jersey City, in the county of Hudson and State of New Jersey, have invented a new and 5 useful Improvement in Rail-Joints and Supports for Elevated Railroads, of which the following is a full, clear, and exact description.

My invention relates to an improvement in rail-joints and supports, especially adapted 10 for use with elevated railways, cylindrical or square rails, and has for its object to provide simple and durable means for uniting the abutting ends of rail-sections; and a further object of the invention is to provide an effective means of tying the rails to an elevated 15 structure and bracing the said rails.

The invention consists in the novel construction of the plate and in the combination with the said plate of a rail-lug; also in the 20 details of the device for connecting the rails and fish-plates.

Reference is to be had to the accompanying drawings, forming a part of this specification, in which similar figures of reference indicate 25 corresponding parts in all the views.

Figure 1 is a side elevation of an elevated structure, illustrating the rails attached thereto by my improved device. Fig. 2 is an end view of Fig. 1. Fig. 3 is an enlarged perspective view of one of the transverse connecting-beams of the structure, illustrating the attachment of the rail thereto. Fig. 4 is a side elevation of Fig. 3, the rail being in section. Fig. 5 is a perspective view of one end of the 30 rail. Fig. 6 is a side elevation of an elevated structure, illustrating the application of the rails thereto and the device for strengthening the said rails. Fig. 7 is a perspective view of one end of the connecting-beams of the structure, enlarged to illustrate the connection of the braces with the plate; and Fig. 8 is a bottom plan view of Fig. 7.

To fully illustrate the application of my invention, I have shown in connection therewith an elevated structure upon which the rails are especially adapted to be laid, the said structure comprising a series of spaced columns 10, united in pairs by transverse beams or girders 11, as shown in Fig. 2, which 45 girders are preferably provided with a smooth flat upper surface, at each end of which girder

11 a T-plate 12 is rigidly secured to the upper surface, the said plate being so secured to the girder that that portion 13 of the plate known as the "head" will lie transversely of the 55 girder, and project a distance beyond the extremity, as best illustrated in Figs. 2, 3, and 7. The attachment of the plates 12 to the girder 11 is usually effected by means of bolts 14 or equivalent fastening devices.

In the head member or section 13 of each plate 12 two spaced longitudinal slots 15 are produced, the inner longitudinal wall of which slots is preferably in vertical alignment with the end of the girder. Each rail-section 65 adapted to be connected or fastened to the girders is provided at or near the extremity with a downwardly-extending, essentially perpendicular, lug 16 integral with the inner face, as illustrated in detail in Fig. 5.

In placing the rails in position the opposed ends are brought together, and the approaching lugs 16 of each section are passed downward through the slots 15 into the T-plate 12 to a contact with the outer end of the girders 70 until the under surface of the rail is brought into immediate contact with the upper face of the plate. The position of the slots 15 with respect to the outer longitudinal edge of the T-plate is so calculated that when the lugs 75 16 are entered into the slots the outer face of the rails 17, which are preferably cylindrical or square, will be in vertical alignment, or essentially so, with the said outer longitudinal edge of the plate, as best shown in Figs. 4 and 85 7. The attachment of the rails to the structure is completed by passing a bolt or bolts 18 through the rail-lugs 16 into the girders.

In operation upon elevated structures the rail-sections are made to abut centrally over 90 each column 10, and in order to strengthen the rail-sections between the columns I provide a truss 19 for each rail-section, the ends whereof are provided with a longitudinal slot 20, through which slots the rail-lugs 16 are 95 made to pass after having been projected through the plate 12, and the bolt or bolts 18 employed to secure the lugs to the girders are passed through the said lugs below the truss, as illustrated in Fig. 7. Thus the truss, 100 which is connected at the center to the under surface of the rail by a block 20, serves not

only to strengthen the rail intermediate of its ends, but also provides a support for the projecting portion of the plate-head 13.

Having thus described my invention, I claim 5 as new and desire to secure by Letters Patent—

1. The combination, with a plate provided with longitudinal spaced slots near one end, of a rail provided with an essentially perpendicular lug integral with the inner face thereof, of which lug is passed downward through one of the slots in the plate, substantially as 10 and for the purpose specified.

2. The combination, with a support and a plate extending beyond the support, provided 15 with spaced longitudinal slots in the projecting end, of rail-sections provided at or near their extremities with an essentially perpendicular lug integral with the inner face, said lugs adapted to be passed downward through 20 the slots in the said plates, substantially as shown and described.

3. The combination, with a support and a plate extending beyond the support, provided 25 with spaced longitudinal slots in the projecting end attached to the said support, of rail-sections provided at or near their extremities with an essentially perpendicular lug integral with the inner face, said lugs adapted to be passed downward through the slots in the 30 said plates, and means, substantially as shown and described, for securing the rail-lugs to the support below the plates, substantially as shown and described.

4. The combination, with a support and a

T-plate rigidly secured to the same, provided 35 with longitudinal spaced slots in the head-section, which head-section extends beyond the end of the support, of rail-sections provided with an essentially perpendicular lug integral with the inner face, passed through 40 the said slots and secured to the ends of the supports, substantially as shown and described, whereby the front of the rail is made to rest upon the upper surface of the plate, and the front of the rail is also brought in 45 vertical alignment with the outer end face of the plate, substantially as shown and described.

5. The combination, with a support, and a T-plate secured to the said support, having slots 50 produced in the head-section, which head-section projects beyond the end of the support, of rail-sections provided with essentially 55 perpendicular lugs integral with the inner face, passed downward through the slots in the plate, a truss of essentially even length with the rail-sections, having slotted ends to receive the rail-lugs below the T-plate, and bolts or other equivalent device for securing the rail-lugs to the end of the support below 60 the truss extremity, substantially as shown and described, whereby the rail is strengthened at the center and the projecting end of the T-plate is supported, as set forth.
